OSCAR C. KREIS, OF DETROIT, MICHIGAN, ASSIGNOR TO CONTINENTAL MOTORS CORPORATION, OF DETROIT, MICHIGAN, A CORPORATION OF VIRGINIA

INTERNAL COMBUSTION ENGINE

Application filed March 5, 1928. Serial No. 259,019.

This invention relates to internal combustion engines and has among its objects the provision of means for improving the general performance of the engine.

5 In engines of the hydrocarbon type it is common practice to employ a carburetor or other mixing device for vaporizing the hydrocarbon with air, the fuel mixture being then conducted to the engine cylinders for combustion. It has been determined that a certain portion of the hydrocarbon is carried along with the fuel mixture in liquid form, not being vaporized by the carburetor. Such a condition is generally prevalent with the 10 present day fuels commonly used for internal combustion engines, and is particularly pronounced in starting an engine as in cold weather or after the engine has been idle for a sufficient length of time to have cooled relative to its normal operating temperature. At such times, and also to a lesser extent during the normal operation of the engine, the wet fuel particles including condensed portions 15 of the fuel mixture tend to collect in the conduit intermediate the carburetor and cylinders, resulting in a sluggish action of the engine, difficulty in starting and generally undesirable engine performance.

20 My invention in its broad aspects is applicable to any type of hydrocarbon engine of the carbureted fuel mixture type. Generic claims embodying my invention are included in my co-pending application Serial No. 251,789 filed February 4, 1928. My present application is directed particularly to means 25 for removing the wet fuel particles especially adapted for poppet valve or like types of engines. This may be done in several ways although I prefer for simplicity and convenience to collect the wet fuel particles and preferably to remove the collected wet fuel particles by suction. Thus I may remove the wet fuel particles by suction derived by the 30 engine piston, the wet particles being conducted from the fuel mixture supply conduit to a suitable point of disposal, preferably into the cylinder separately from the supply conduit. By such a general engine construction I have greatly improved the starting 35

ability of the engine as well as overcoming the sluggish action of the engine.

One important application of my present invention relates to poppet valve or like types of engines as distinguished from sleeve valve 55 engines. I have illustrated my invention in connection with a typical well known type of engine known as the L-head type, although as aforesaid my invention is also applicable to other general types of engines and valve 60 arrangement. It is not my purpose therefore to limit my invention except as specifically recited in the appended claims.

In the accompanying drawings in which like reference characters indicate corresponding parts,

Fig. 1 is a sectional view through one of the cylinders and intake manifold of a typical poppet valve engine, illustrating my invention, and

Fig. 2 is a detail view of the engine with the piston completing the intake stroke.

Referring to the drawings reference character 10 illustrates the engine cylinder block having cylinders 11 jacketed at 12 for circulation of a cooling fluid. The cylinder ends are closed by the usual cylinder head 13 to provide a valved combustion chamber 14. The usual intake and exhaust valves may be provided for each chamber 14, the intake 75 valve being illustrated at 15 controlling intake port 16. The intake port 16 communicates with the fuel mixture supply manifold 17 through cylinder intake passage 18 it being understood that branch passages 18 are 80 provided singly or in groups for the various intake ports of the various cylinders of the engine. 19 represents a conventional carburetor for supplying carbureted commercial gasoline or other hydrocarbon to the intake 85 manifold. The engine thus far described is in the main conventional and well known, further description of the details being deemed unnecessary for the purpose of a full and comprehensive disclosure of my invention.

In order to collect or concentrate the unvaporized and condensed particles of hydrocarbon and fuel mixture passing from the carburetor 19 to the intake ports 16 I pro- 90

vide one or more traps 20 for each cylinder conduit 18 or the trap may be constructed in the nature of a header for a plurality of the conduits 18. The floor of the conduit 18 is ordinarily sloped downwardly and outwardly from port 16 to the side of the cylinder block 10 so that any wet particles tending to form or collect in this portion of the fuel mixture supply system will drain by gravity toward and into the trap 20. The wet particles collected in the trap 20 may be disposed of as desired, it being one feature of my invention to provide means for conducting the wet particles by suction into one or more cylinders of the engine. Thus the trap 20 communicates with a port 21 in the cylinder wall, a suitable conduit 22 conducting the wet particles from the trap 20 to the port 21. Interposed at a convenient point in the drain system is a valve chamber 22 and associated check valve 23 yieldingly urged to its seat by a spring 24.

The port 21 is suitably timed with respect to the engine piston 25 so as to be uncovered by the downward travel of the piston, preferably toward the end of the piston downward stroke.

In operation, assuming the piston 25 as in Fig. 1 on its downward intake stroke, the port 21 is preferably covered by the piston during its initial downward travel and the valve 23 is seated by reason of spring 23. As the intake stroke continues the piston uncovers port 21 as in Fig. 2 and the suction within the engine cylinder created by the piston will act in conduit 22 to unseat the valve 23. Thus, the wet fuel mixture particles, drained by the intake system proper and collected in trap 20 will be removed from the intake system and passed through the conduit 22 into the engine cylinder. On the upward compression stroke and upward exhaust stroke of the piston, the pressure in the cylinder and in conduit 22, during that portion of the stroke when port 21 is open to the cylinder, will act with spring 24 to keep the valve 24 seated. Similarly when the explosion or working downward stroke of the piston takes place the cylinder pressure will keep the valve 23 seated. By varying the position of port 21 with respect to the piston stroke the degree and duration of suction exerted in conduit 22 may be varied as desired under the circumstances.

By reason of my invention the wet fuel particles are removed from the fuel intake system between the carburetor and cylinder intake ports as fast as they accumulate. Any wet particles collecting between successive intake strokes for any cylinder will build up in the trap 20 at the rear of valve 23 and will be removed at the next suction stroke. The relatively small capacity of the conduit 22 with respect to the intake manifold 17 is not

sufficient to interfere with the normal functioning of the engine intake.

I prefer to provide a conduit 22 for each engine cylinder in order to obtain the same conditions of operation for each engine cylinder although if desired for simplicity the wet fuel particles may be conducted from the intake system to any one or more cylinders.

What I claim as my invention is:

1. In an internal combustion engine, a cylinder, a conduit for supplying a vaporized hydrocarbon to the cylinder, a second conduit communicating with the first said conduit and with the cylinder independently of the first said conduit for removing therefrom unvaporized portions of the hydrocarbon, and a check valve controlling the said second conduit. 75

2. In an internal combustion engine, a cylinder, a conduit for supplying a vaporized hydrocarbon to the cylinder, a second conduit directly communicating with the cylinder and also communicating with first said conduit for removing therefrom unvaporized portions of the hydrocarbon, an intake valve for the first conduit, and valve means for the second conduit. 85

3. In an internal combustion engine, a conduit for supplying a vaporized hydrocarbon to the engine, a second conduit communicating with the first said conduit for removing therefrom unvaporized portions of the hydrocarbon, a cylinder and associated piston, and a valve in the second conduit adapted to be unseated by the suction created in the cylinder by the piston. 95

4. In an internal combustion engine having a cylinder and associated piston, the piston having sliding contact with the cylinder, a fuel mixture intake system for the cylinder, valve means between the cylinder and intake system controlling the supply of fuel mixture to the cylinder, a suction conduit communicating with the cylinder independently of the intake system and also communicating with the intake system for removing therefrom unvaporized portions of the fuel mixture, and a valve controlling said conduit. 105

5. In an internal combustion engine having a cylinder and associated piston, a fuel mixture intake system for the cylinder, valve means between the cylinder and intake system controlling the supply of fuel mixture to the cylinder, a suction conduit communicating with the intake system for removing therefrom unvaporized portions of the fuel mixture, said suction conduit communicating with the cylinder independently of said intake system, and a check valve controlling said conduit. 115

6. In an internal combustion engine having a cylinder and associated piston, the piston having sliding contact with the cylinder, a fuel mixture intake system for the cylinder, valve means between the cylinder and intake

- system controlling the supply of fuel mixture to the cylinder, a suction conduit communicating with the intake system for removing therefrom unvaporized portion of the fuel mixture, a cylinder port positioned with respect to the piston travel so as to be uncovered by the piston during the downward intake stroke of the piston, said conduit communicating with said cylinder port.
7. In an internal combustion engine having a cylinder and associated piston, the piston having sliding contact with the cylinder, a fuel mixture intake system for the cylinder, valve means between the cylinder and intake system controlling the supply of fuel mixture to the cylinder, a suction conduit communicating with the intake system for removing therefrom unvaporized portion of the fuel mixture, a cylinder port positioned with respect to the piston travel so as to be uncovered by the piston during the downward intake stroke of the piston, said conduit communicating with said cylinder port, and valve means controlling said conduit.
8. In an internal combustion engine having a cylinder and associated piston, a fuel mixture intake system for the cylinder, valve means between the cylinder and intake system controlling the supply of fuel mixture to the cylinder, a suction conduit communicating with the intake system for removing therefrom unvaporized portion of the fuel mixture, a cylinder port positioned with respect to the piston travel so as to be uncovered by the piston during the downward intake stroke of the piston, said conduit communicating with said cylinder port, and a valve in the conduit adapted to be unseated by the suction created in the cylinder by the piston.
9. In an internal combustion engine, a cylinder block having a cylinder, a piston slidably contacting with the cylinder, an intake valve, a fuel mixture supply system including a cylinder block intake passageway controlled by said intake valve, said passageway having a floor sloping generally downwardly from said valve and outwardly of the cylinder block, a trap collecting wet fuel mixture particles drained by said sloping floor, and a conduit opening to the cylinder and said trap, and a valve controlling said conduit.
10. In an internal combustion engine, a cylinder block having a cylinder, a piston, an intake valve, a fuel mixture supply system including a cylinder block intake passageway controlled by said intake valve, said passageway having a floor sloping generally downwardly from said valve and outwardly of the cylinder block, a trap collecting wet fuel mixture particles drained by said sloping floor, a conduit opening to the cylinder and said trap, and a valve in the conduit adapted to be unseated by the suction created in the cylinder by the piston.
11. In an internal combustion engine of the poppet valve L-head type including a cylinder block having a cylinder and associated piston, a cylinder block intake passage extending from the side of the cylinder block upwardly and inwardly thereof, a poppet valve controlling the supply of fuel mixture to the cylinder through said passageway, an intake manifold communicating with said passageway, a carburetor supplying vaporized hydrocarbon to said manifold, a cylinder port positioned with respect to the piston travel so as to be uncovered by the piston during its intake stroke, a trap adapted to collect wet fuel mixture particles drained by said passageway, a conduit communicating with the cylinder port and with the trap, and a valve controlling the said conduit.
12. In an internal combustion engine of the poppet valve L-head type including a cylinder block having a cylinder and associated piston, a cylinder block intake passage extending from the side of the cylinder block upwardly and inwardly thereof, a poppet valve controlling the supply of fuel mixture to the cylinder through said passageway, an intake manifold communicating with said passageway, a carburetor supplying vaporized hydrocarbon to said manifold, a cylinder port positioned with respect to the piston travel so as to be uncovered by the piston during its intake stroke, a trap adapted to collect wet fuel mixture particles drained by said passageway, a conduit communicating with the cylinder port and with the trap, and a check valve in said conduit adapted to unseat as the piston uncovers the said port during the intake stroke of the piston.
13. In an internal combustion engine having a cylinder and associated piston, the piston having sliding contact with the cylinder, a fuel mixture intake system for the cylinder, valve means between the cylinder and intake system controlling the supply of fuel mixture to the cylinder, a suction conduit communicating with the intake system for removing therefrom unvaporized portions of the fuel mixture, and a valve controlling said conduit, said second valve adapted to unseat only during at least a portion of the engine intake cycle.
14. In an internal combustion engine, a conduit for supplying a vaporized hydrocarbon to the engine, a second conduit communicating with the first said conduit for removing therefrom unvaporized portions of the hydrocarbon, a cylinder and associated piston, and a valve in the second conduit adapted to be unseated by the suction created in the cylinder by the piston, only during at least a portion of the piston suction stroke.
15. An internal combustion engine comprising in combination, a cylinder, a piston having sliding contact with the cylinder, fuel mixture supply means for the cylinder, valve

means controlling the passage of fuel mixture to said cylinder, means in direct communication with the cylinder and also in communication with the fuel mixture supply means for removing therefrom unvaporized portions of the fuel mixture, and a second valve means for the said communication means.

16. An engine comprising in combination, a cylinder, a piston therein having sliding contact with the cylinder, a fuel mixture intake system for the cylinder, valve means controlling said intake to the cylinder, means communicating with the intake system for conducting therefrom unvaporized portions of the fuel mixture to said cylinder independently of the intake system, and valve means controlling said conducting means.

17. An engine comprising in combination, a cylinder, a piston therein having sliding contact with the cylinder, a fuel mixture intake system for the cylinder, valve means controlling said intake to the cylinder, means communicating with the intake system for conducting therefrom unvaporized portions of the fuel mixture to said cylinder independently of the intake system, and means controlled by said piston for inducing passage of the unvaporized portions of the fuel mixture into the cylinder.

18. An engine comprising in combination, a cylinder, a piston therein having sliding contact with the cylinder, a fuel mixture intake system for the cylinder, valve means controlling said intake to the cylinder, and valve controlled suction means inducing removal of unvaporized portions of the fuel mixture from the intake system.

19. An engine comprising in combination, a cylinder, a piston therein, a fuel mixture intake system for the cylinder, and valve means controlling said intake to the cylinder, and valve controlled suction means inducing removal of unvaporized portions of the fuel mixture from the intake system, the last named means being automatically actuated in response to suction created by the intake stroke of the piston.

20. In an internal combustion engine having a cylinder and associated piston, a fuel mixture intake system for the cylinder, valve means between the cylinder and intake system controlling the supply of fuel mixture to the cylinder, a suction conduit communicating with the intake system for removing therefrom unvaporized portions of the fuel mixture, and a valve controlling said conduit, said second valve adapted to unseat only during the latter portion of the engine intake cycle.

21. In an internal combustion engine, a conduit for supplying a vaporized hydrocarbon to the engine, a second conduit communicating with the first said conduit for removing therefrom unvaporized portions of the hydrocarbon, a cylinder and associated piston, and a valve in the second conduit adapted

to be unseated by the suction created in the cylinder by the piston, only during the latter portion of the piston suction stroke.

In witness whereof, I hereunto subscribe my name this 29th day of February, A. D. 1928.

OSCAR C. KREIS.
